FASTENING DEVICE

Filed Jan. 21, 1925

INVENTOR
Davis Marinsky
BY
Howard E. Thompson
ATTORNEY

UNITED STATES PATENT OFFICE.

DAVIS MARINSKY, OF BRONX, NEW YORK.

FASTENING DEVICE.

Application filed January 21, 1925. Serial No. 3,739.

REISSUED

To all whom it may concern:

Be it known that I, DAVIS MARINSKY, a citizen of the United States, and residing at Bronx, in the county of Bronx and State of New York, have invented certain new and useful Improvements in Fastening Devices, of which the following is a specification, such as will enable those skilled in the art to which it appertains to make and use the same.

This invention relates to fastening devices and particularly to devices of this class adapted to couple and uncouple two or more parts together to retain said parts in locked position against accidental displacement when coupled together; and the object of the invention is to provide a device of the class and for the purpose specified, the separate cooperative members of which are each constructed of a strand of predetermined material upon which are mounted, in juxtaposition, independent catch devices fashioned from rods or wires and said devices being secured to said strand to retain the same in predetermined position thereon; a further object being to provide means for covering or sealing that portion of said devices mounted upon said strand to form a neat and finished appearance to said members and to facilitate the mounting thereof in connection with suitable supports; a further object being to provide means for moving of said members into interlocked position and to separate said members in coupling and uncoupling two parts or bodies; a still further object being to provide means adapted to be passed through the catch devices of the interlocked members for positively retaining said members against separation; and with these and other objects in view, the invention consists in a device of the class and for the purpose specified, which is simple in construction, efficient in use and which is constructed in accordance with the method hereinafter more fully described and claimed.

The invention is fully disclosed in the following specification, of which the accompanying drawing forms a part, in which the separate parts of my improvement are designated by suitable reference characters in each of the views, and in which:

Fig. 1 is a perspective view of an over-

shoe illustrating one use of my invention mounted in connection therewith. 55

Fig. 2 is a detail view of a part of a fastening device made according to my invention and indicating the method of its use.

Fig. 3 is a sectional, detail view of a part of the construction shown in Fig. 2. 60

Fig. 4 is a perspective detail view of a modified form of device which I may employ.

Fig. 5 is a plan view of an eyelet through which one of the links or catch devices of my invention is formed. 65

Fig. 6 is a view similar to Fig. 5 showing the link partially formed.

Fig. 7 is a side edge view of the link shown in Fig. 6 and illustrating the final step in completing the formation thereof. 70

Fig. 8 is a detail view illustrating the method of mounting the links or catch devices upon a strand or binder.

Fig. 9 is a sectional view on an enlarged scale showing the method of securing the links against displacement on the strand or binder. 75

Fig. 10 is a partial section on the line 10—10 of Fig. 2 on an enlarged scale. 80

Fig. 11 is a diagrammatic sectional view illustrating the method of applying the casting or attaching strip; and, 85

Fig. 12 is a diagrammatic view illustrating a modified use of the invention showing means for positively retaining the devices against separation. 90

My invention relates to fastening devices as are in common use in securing two or more parts or bodies together to retain the same against accidental displacement as for example, securing the flaps or wings of a shoe or overshoe together, forming a closure for a tobacco pouch or other container, and like uses; but the principal object of my invention is to provide a fastening device of the class specified which may be manufactured at a nominal cost as compared with other devices of this class and yet produce a strong and durable, flexible as well as practical device and which by reason of its construction may be readily manufactured. 95

In carrying my invention into effect, I 100

employ a plurality of links or catch devices 20, which in the construction shown are preferably in the form of an eyelet, commonly known in the art of fastening devices, said eyelet having a large central loop 20^a and smaller loops 20^b and 20^c disposed at the side portions of the large loop. The first step in the process of forming my improved fastening device or the separate members thereof, the link 20 is fashioned to bring the loops 20^b and 20^c thereof into juxtaposition side by side and in axial alignment, after which or in the same operation, the large loop 20^a is fashioned to form a concave face 20^d and convex face 20^e or into substantially hook formation as clearly seen in Fig. 7 of the drawing, it being understood that said concave and convex faces extend transversely of the link as viewed from one side thereof.

After the links 20 have been formed in the manner above described or produced from a piece of wire fashioned directly into the form shown in Fig. 7 by means of a suitable machine, said links are placed upon a mounting strand or body 21 which may be a piece of fabric, string, cord and the like or a piece of wire cable or similar flexible and strong and durable material in the manner partially indicated in Fig. 8 of the drawing so that the loops 20^b and 20^c of the separate links lie snugly one upon the other, the double loops serving to equally space the links 20 one from the other when mounted upon the strand or mounting 21 as clearly seen in Fig. 8 of the drawing. After the required number of the links 20 have been mounted on the strand 21, the loop portions 20^b and 20^c thereof are compressed laterally to securely retain the links against shifting upon the strand 21 and to key said links against rotation, it being seen on a consideration of Fig. 8^a of the drawing that the strand 21 is compressed as shown at 21^a in the above operation, and the loops 20^b and 20^c flattened to form elongated loops, the openings of which are similar in form to the cross section of said strand.

I also employ a casing or finishing strip 22 which may be composed of any desired material but preferably a fibrous material, and this casing or strip is provided centrally and longitudinally thereof with spaced apertures 22^a of such dimensions as to receive and frictionally pass over the loops 20^a of the links 20, and said apertures are divided by transverse members 22^b which are adapted to be positioned between the separate loops 20^a when the casing or strip is mounted upon the strand 21 with the links 20 thereon.

In Fig. 11 of the drawing, I have indicated the method of passing the loops 20^a through the strip 22 and in dotted lines, I have shown the strip 22 folded around the

strand 21 and the loops 20^b and 20^c thereon to enclose the bound ends of the links and to form a casing or finishing strip therefor. The strip 22 is also preferably used in securing the separate fastening devices made in the manner set out to predetermined articles or devices such for example as the flaps or wings 23 and 24 of an overshoe or similar article as seen in Fig. 1 of the drawing and also indicated in Fig. 2 of the drawing. 75

It will be understood that after the separate parts of one fastening device have been made in accordance with the above method and of a required length and with links of the required size or dimensions, the separate parts of the fastening device are coupled together by a coupling block 25 substantially V-shaped in form in plan, and as shown in Figs. 2, 3 and 10 of the drawing is fashioned from a single metallic body open 80 at one end as shown at 25^a in the form of a single passage and the opposite end portion of which is divided into separate passages 25^b and 25^c by a V-shaped partition wall 25^d while the sides of the body are also provided with apertures 25^e and 25^f opening 90 through the opposite ends of the body and outwardly through said sides and into the passages thereof. The apertures 25^e and 25^f are formed by inwardly directed flanges 25^g 95 at the opposite sides of said block as clearly seen in Fig. 10 of the drawing.

In Fig. 2 of the drawing, I have indicated at 26 and 27 two independent parts of a fastening device, said parts being joined or coupled together at one end, the end 28 indicated in Fig. 1 of the drawing in the usual or any desired manner, while the other end portions are free and adapted to be moved toward and from each other in the 100 operation of my fastening device, the last named end portions having stop members 29 to limit the movement of the coupling block 25 and to prevent the displacement of said block from the separate members 26 and 27. The pointed end portion of the block 25 or the end portion provided with the aperture 25^a is directed toward the attached end of the members 26 and 27 and said block is mounted upon and adapted to move longitudinally of said members to 105 couple and uncouple the same in the operation of opening and closing the flaps 23 and 24 of an overshoe or in coupling and uncoupling any two bodies by the use of my improved fastening device. In the above operation of sliding the block 25 longitudinally of the members 26 and 27, the member 26 passes through the aperture 25^b of 110 said block while the member 27 passes 115 through the aperture 25^c thereof and said members are brought together and the links 20 thereof interlock in the manner shown in Figs. 2 and 10 of the drawing as they 120 pass through the aperture 25^a of said block, 125 130

this result being accomplished in the upward movement of the block while in the downward movement thereof, the V-shaped partition wall 25^a as well as the apertures 25^b and 25^c operate to separate the links one from the other in separating the members 26 and 27.

It will be seen on a consideration of Figs. 2 and 3 of the drawing that the links 20 of the separate members 26 and 27 interlock with the other in a substantial degree and the curved portions of the loops 20^a thereof interlock with each other to prevent the separation of said links when subject to lateral stress or in other words, the concave faces of oppositely disposed links rest one within the other to form an interlocking construction or a substantially hook-shaped lock. By reason of the fact that the outer end portion of the links 20 of one of the members 26-27 interlocks with the corresponding end portion of the links 20 of the other of said members, said links are also retained against transverse displacement or side movement one upon the other when said links are coupled together. It will also be noted that the flanges 25^e cooperate with the loops 20^a of the links in the coupling and uncoupling of the members 26 and 27.

The coupling block 25 is also preferably provided with a finger piece 30 movably disposed on said block or a member 31 thereon to facilitate the manipulation of said block. It will be understood that the strips 22 are stitched or otherwise secured to the flaps 23 and 24 or to the other bodies or parts in connection with which the members 26 and 27 are employed.

In Fig. 12 of the drawing, I have diagrammatically illustrated a modified use of the invention in which a locked rod 32 is used in connection with the members 26 and 27 and is adapted to be passed through the loops 20^a of both of said members for positively locking the same against forcible displacement or separation, the rod being headed at one end as shown at 33 and provided with an aperture 34 at the other end to facilitate the placement of a seal, lock or the like on the last named end portion to prevent the rod from being accidentally or otherwise removed from the members 26 and 27. It will be understood that the members 26 and 27 have not been shown completely in Fig. 12 as said figure is only diagrammatically illustrative, and this particular use of the invention might be applicable to many articles or containers, such for example as mail bags.

In Fig. 4 of the drawing, I have shown the separate parts of a modified form of coupling block 35 which is of the same general shape and form as the block 25 herefore described but which is composed of sheet metal having top and bottom plates

36 and 37 of similar form and construction and an intermediate partition wall plate 38 V-shaped in form and having upwardly and downwardly directed prongs 39 adapted to enter apertures 40 in the plates 36 and 37 for securing the parts 36, 37 and 38 together. Only one side of the prongs 39 is shown and the apertures 40 in the plate 36 only is shown, the plate 38 being shown mounted upon and secured to the plate 37 by the prong and aperture construction above described.

It will be understood however, that my invention is not necessarily limited to any specific method of constructing the coupling block 25 nor to the use of the attaching or finishing strip constituting a casing for the separate parts of the fastening device, nor am I necessarily limited to the specific shape or form of the separate links employed and particularly the shape or form of the loops 20^a thereof and various other changes in and modifications of the construction herein shown and described may be made within the scope of the appended claims without departing from the spirit of my invention or sacrificing its advantages.

It will also be understood that in my improved method of making fastening devices of the class under consideration, a coating or plating may be readily applied to the links to give a color thereto which will be in harmony with the article in connection with which the device is used; such for example, as a coating of paint or enamel or similar liquid, or a nickel, silver or gold or platinum plating, or plating of any other metal, which result can readily be accomplished in using a metallic strand, and this is one of the distinctive features of my invention.

Having fully described my invention, what I claim as new and desire to secure by Letters-Patent, is:—

1. A device of the class described comprising two coupling bodies, each of said bodies comprising a plurality of independently formed link members, means for mounting said link members one upon the other and in common alinement and for coupling said link members together with that portion of said members on said means in juxtaposition and abutting, said mounting means being flexible, and means movably disposed on said bodies for coupling and uncoupling the same.

2. A device of the class described comprising two coupling bodies, each of said bodies comprising a plurality of independently formed link members, means for mounting said link members one upon the other and in common alinement and for flexibly coupling said link members together, the parts of said link members on said means being in juxtaposition and abutting and

thicker than the free parts thereof for spacing said free parts one from the other, and a coupling block movably disposed on said bodies for coupling and uncoupling the 5 same.

3. A device of the class described comprising two coupling bodies each of said bodies comprising a plurality of independently formed link members, means for 10 mounting said link members one upon the other and in common alinement and for flexibly coupling said link members together, the parts of said link members on said means being in juxtaposition and abutting 15 and thicker than the free parts thereof for spacing said free parts one from the other, said link members being secured to said first named means in such a manner as to prevent the lateral movement of said link members thereon, and a coupling block movably 20 disposed on said bodies for coupling and uncoupling the same.

4. A device of the class described comprising two coupling bodies, each of said bodies 25 comprising a plurality of independently formed link members, means for mounting said link members one upon the other and in common alinement and for flexibly coupling said link members together, the parts 30 of said link members on said means being in juxtaposition and abutting and thicker than the free parts thereof for spacing said free parts one from the other, said link members being secured to said first named means in 35 such a manner as to prevent the lateral movement of said link members thereon, a casing mounted upon said first named means and encircling predetermined portions of said link members, and a coupling block 40 movably disposed on said bodies for coupling and uncoupling the same.

5. A device of the class described composed of two coupling bodies, each of said bodies comprising a plurality of independently formed link members, means for 45 mounting said link members one upon the other and in common alinement and for coupling said link members together, the parts of said link members on said means 50 being in juxtaposition and abutting, said mounting means being flexible, means on said link members for spacing the same one from the other, said link members being secured to said first named means in such 55 manner as to prevent lateral movement of said link members thereon, a casing mounted upon said first named means and encircling predetermined portions of said link members and said casing having a projecting portion 60 to facilitate the mounting thereof in connection with a suitable support, and a coupling member movable on said bodies for coupling and uncoupling the same.

6. A fastening device of the class de- 65 scribed comprising separate members adapt-

ed to be coupled and uncoupled one with the other, means movably disposed thereon for coupling and uncoupling said members, each of said members comprising a mounting strand and a plurality of independently 70 formed links mounted directly upon said strand with that portion of the links on said strand in juxtaposition and abutting and fixedly secured thereto.

7. A fastening device of the class described 75 comprising separate members adapted to be coupled and uncoupled one with the other, means movably disposed thereon for coupling and uncoupling said members, each of said members comprising a mounting strand 80 and a plurality of independently formed links mounted directly upon said strand with that portion of the links on said strand in juxtaposition and abutting and fixedly secured thereto, and the projecting portion 85 of the links of said members being in spaced relation and adapted to interlock.

8. A fastening device of the class described comprising separate members adapted to be coupled and uncoupled one with the 90 other, means movably disposed thereon for coupling and uncoupling said members, each of said members comprising a mounting strand and a plurality of independently 95 formed links mounted directly upon said strand with that portion of the links on said strand in juxtaposition and abutting and fixedly secured thereto, the projecting portion of the links of said members being in spaced relation and adapted to interlock, 100 said projecting portion being hook-shaped in form, and means movably disposed longitudinally of the separate members for moving the projecting hook-shaped portions of the links thereof into and out of engagement with each other.

9. A fastening device of the class described comprising separate members adapted to be coupled and uncoupled one with the other, each of said members comprising a 110 mounting strand and a plurality of independently formed links mounted upon said strand in juxtaposition and fixedly secured thereto, the projecting portion of the links of one of said members being adapted to interlock with the projecting portions of the links of the other member, means movably disposed longitudinally of the separate members for moving the projecting portions of the links thereof into and out of engagement with each other, and the links of one of said members having upwardly curved 115 portions while the links of the other member are provided with downwardly curved portions to prevent separation of said members when coupled together.

10. A fastening device of the class described comprising separate members adapted to be coupled and uncoupled one with the 120 other, each of said members comprising a 125

- mounting strand and a plurality of independently formed links mounted upon said strand in juxtaposition and fixedly secured thereto, the projecting portion of the links 5 of one of said members being adapted to interlock with the projecting portions of the links of the other member, means movably disposed longitudinally of the separate members for moving the projecting portions 10 of the links thereof into and out of engagement with each other, the links of one of said members having upwardly curved portions while the links of the other member are provided with downwardly curved portions 15 to prevent separation of said members when coupled together, and means on each of said link members for equally spacing the same one from another on the separate strands.
- 20 11. A fastening device of the class described comprising separate members adapted to be coupled and uncoupled one with the other, each of said members comprising a mounting strand and a plurality of independently formed links mounted upon said strand in juxtaposition and fixedly secured thereto, the projecting portion of the links of one of said members being adapted to interlock with the projecting portions of the 25 links of the other member, means movably disposed longitudinally of the separate members for moving the projecting portions of the links thereof into and out of engagement with each other, the links of one of said members having upwardly curved portions 30 while the links of the other member are provided with downwardly curved portions to prevent separation of said members when coupled together, means on each of said link members for equally spacing the same one from another on the separate strands.
- 35 12. A fastening device of the class described comprising separate members adapted to be coupled and uncoupled one with the other, each of said members comprising a mounting strand and a plurality of independently formed links mounted upon said strand in juxtaposition and fixedly secured thereto, the projecting portion of the links of one of said members being adapted to interlock with the projecting portions of the 40 links of the other member, means movably disposed longitudinally of the separate members for moving the projecting portions of the links thereof into and out of engagement with each other, the links of one of said members having upwardly curved portions 45 while the links of the other member are provided with downwardly curved portions to prevent separation of said members when coupled together, means on each of said link members for equally spacing the same one from another on the separate strands.
- 50 13. A device of the class described composed of two coupling bodies, each of said bodies comprising a mounting strand and a plurality of links adapted to be mounted on said strand, with that part of the links on said strand in juxtaposition and abutting, the other part of said links projecting radially from said strand in longitudinal alinement and equally spaced one from the other by 55 the first named part of said links, and means movably disposed on said bodies for coupling and uncoupling the same.
- 60 14. A device of the class described comprising a mounting strand and a plurality of links adapted to be mounted on said strand, with that part of the links on said strand in juxtaposition, the other part of said links projecting radially from said strand in longitudinal alinement and equally spaced one from the other by 65 the first named part of said links, the projecting portions of said links being in the form of closed loops, the outer end portions of which are fashioned to form hook-shaped ends, and means movably disposed with relation to said link members for coupling and uncoupling the same.
- 65 15. A device of the class described composed of two coupling bodies, each of said bodies comprising a plurality of independently formed wire link members, said link members being composed of three single loops, two of which are adapted to be brought together in common alinement and the other of which projects radially from the first named loops, a mounting strand upon which said link members are mounted, said strand passing through the first named 70 loops of said link members and said loops being secured to said strand, and a coupling member movably disposed on said bodies for coupling and uncoupling the same.
- 75 16. A device of the class described comprising a plurality of independently formed wire link members, having projecting closed loop portions, means for coupling said link members together in close proximity and with said loop portions in axial alignment.
- 80 17. A device of the class described comprising a plurality of independently formed wire link members, having projecting closed loop portions, means for mounting said link members upon one another with said loop portions in common axial alignment and for coupling said link members together with that portion of said link members on said means in juxtaposition and abutting.
- 85 18. A device of the class described comprising a mounting strand and a plurality of

5 of wire links mounted on said strand with that part of the links on said strand in juxtaposition and abutting, the other part of said links comprising closed loop portions projecting radially from said strand in longitudinal axial alignment and equally spaced one from the other by the first named part of said links.

19. A fastening device comprising two 10 coupling bodies, each of said bodies comprising a plurality of independently formed wire link members mounted upon a flexible strand, and having projecting closed loop portions in longitudinally axial alignment 15 and means movably disposed on said bodies for coupling and uncoupling the link members of one body with relation to the other.

20. A fastening device comprising two coupling bodies, each of said bodies comprising a plurality of independently formed wire link members mounted upon a flexible strand, and having projecting closed loop portions in longitudinally axial alignment means movably disposed on said bodies for coupling and uncoupling the link members 25 of one body with relation to the other, and means for mounting said bodies in connection with a suitable support, said means engaging said flexible strand and the link members mounted thereon.

In testimony that I claim the foregoing as my invention I have signed my name this 16th day of Jan. 1925.

DAVIS MARINSKY.
